CATTLE GUARD

S. Irma Smith, Springfield, Mo.

Application October 20, 1936, Serial No. 106,679

7 Claims. (Cl. 256—14)

This invention relates to cattle guards, and in general, aims to provide improvements in the cattle guard disclosed in Patent No. 1,314,910 which issued to me on September 2, 1919. While the said patented cattle guard is of proven utility, because of its construction it is difficult to install on a curved railroad track or when there are two or more tracks especially if of different elevation. Hence when installing the patented cattle guard, sometimes half A frames are placed between each track, which is objectionable as a hazard is thus created.

The present invention provides a cattle guard which is so made that it may be installed under a curved as well as a straight track and may be built up to provide a continuous guard for any number of adjacent tracks; in short, the invention provides a universal cattle guard, having all the utility of the patented guard with none of its drawbacks.

In the accompanying drawings forming a part of this specification and showing a preferred embodiment of the invention,—

Fig. 1 is a plan view of the cattle guard, shown installed beneath a straight section of track;

Fig. 2 is a vertical section, on line 2—2 of Fig. 1;

Fig. 3 is a vertical cross section on line 3—3 of Fig. 2;

Fig. 4 is a perspective view of several of the members which, when connected together, make up the body of the cattle guard;

Fig. 5 is a side elevation of several of the members, showing how their angles and relative positions may be varied;

Fig. 6 is an end elevation of one of the members; and

Fig. 7 is a section on line 7—7 of Fig. 5.

Referring particularly to the drawings, the improved cattle guard employs the usual or standard A-frames 10 which need not be described and the usual ridged or peaked wooden strips 11 which are nailed to the tops of the ties 12. The rails 13 of a single track are also shown so that the position of the improved cattle guard when installed may be understood.

The main body of the cattle guard comprises a series of baffles each of which is adapted to fit the space between two adjacent railroad ties. Each baffle comprises a plurality of units or members which are best illustrated in Figs. 4—7, inclusive. As the baffles are made up of a plurality of more or less aligned units or members connected together, each baffle is of indefinite length and

may be extended beneath two or more tracks if desired.

Referring particularly to Fig. 4, each baffle comprises a series of flanged plates which are generally U-shaped, that is each flange plate comprises an end plate 14 integral with flanges 15, the end plates 14 adapted to stand inclined relative to the vertical when the plates are assembled to form a baffle. The upper edges of each of the end plates 14 may be serrated as shown at 16 to make it more difficult for cattle to walk upon them. Each of the flanges 15 is preferably cut away as indicated at 15a and thus integral with each flange 15 there is a pair of arms 17 and 18 which extend horizontally and which lie in the same plane with the normally vertical flanges 15. Preferably the arms 17 and 18 are slightly spread apart so that the plate members may be nested, which is a great convenience in shipping and storing said members. This slight spreading of the arms 17 and 18 also facilitates the attachment of the members end to end as illustrated in Figs. 4 and 5. Attachment is preferably effected by means of upper and lower bolts 19 which are received in bolt holes 20 and 21 respectively in the upper and lower arms 17, 18, and which pass through holes 22 and 23 in the flanges 15 adjacent the end plates 14. The arms of each plate member are outside of the adjacent plate member and the bolts are passed first through said arms and then through holes adjacent the end plates 14, as shown, thus connecting the U-shaped members in a longitudinal series to form the complete baffle. The height of the plate members is approximately the thickness of a railroad tie and the width of each plate member is substantially the distance between two such ties, so that the baffle formed from a plurality of plate members substantially fills the space between each tie. See Figs. 1 and 3.

Preferably the plate members are made of sheet steel galvanized for protection against the weather, initially of the form shown in Fig. 6. Afterwards they may be bent into the shape shown in Fig. 4.

The described construction permits the plates to be directly aligned with each other, that is, to form a continuous straight member, as shown in Fig. 4, or if desired adjacent plate members may be set at angles to each other, as shown at the left end of Fig. 5. This permits the baffles to be longitudinally curved so as to be adaptable to a curved track which always has one rail higher than the other. If the baffles are to be

placed under two tracks having rails lying at different elevations, some of the plate members may be offset relative to each other, as clearly shown at the right end of Fig. 5. This peculiar adaptability of the plate members to different conditions found in the field is the principal improvement provided by the present invention. The feature of nesting the plate members, which when nested may be bound into bundles, is also an important advance over the construction shown in the aforesaid patent.

It will be clear, from the foregoing, that the cattle guard of the invention may be installed under any track or series of tracks, and when so installed, will bar the movement of cattle over it as effectively as does the patented cattle guard. A further advantage is that the members which are assembled to make up the body of the cattle guard are standardized, and may be nested to make up bundles for economical shipment, handling and storage. While I have shown the members as provided with a series of bolt holes, for the adjustments described above, obviously they may have arcuate slots or other known mechanical connecting means which permit disalignment of adjacent connected members.

Obviously the present invention may be embodied in several forms, neither described nor shown, though within the scope of the appended claims.

Having described a preferred embodiment of the invention, what I claim as new and desire to secure by Letters Patent is:

1. An article of manufacture comprising a unitary member which may be assembled with other like members to form the body of a cattle guard, said member comprising a plate which is adapted to stand at an angle to the vertical and which has a thin upper edge; a pair of flanges integral with the plate and extending parallel to each other, being vertical when the plate is in its normal position; and means on the flanges to facilitate connection, by means of bolts or the like, of two or more members to each other.
2. The invention according to claim 1 wherein the flanges are each cut away to provide two horizontally extending arms, and the means to facilitate connection comprise a series of holes in

said arms and in the flanges adjacent the plates, said holes being so arranged as to permit angular adjustment or offsetting of two connected members.

3. A cattle guard comprising, in combination, 5 a plurality of baffles each consisting solely of a plurality of flanged plates connected together; said baffles each being of a width approximating the distance between two standard railroad ties and being adapted to be set between said ties and 10 being of a length determined by the number of flanged plates which are connected together; a plurality of ridged wooden strips secured to the tops of all the ties which are adjacent said baffles; and A-frames secured at either end of 15 the guard to the ends of said baffles.

4. The invention according to claim 3 wherein the flanged plates are so constructed and arranged that they may be offset or set at acute angles relative to each other or may be alined end to end 20 with each other and secured by simple connecting elements which fix them in their set positions.

5. The invention according to claim 3 wherein the flanged plates have end faces which lie at an angle to the vertical, and the flanges thereof are 25 substantially vertical and are cut away to provide a pair of arms extending horizontally from each flange, the extremities of said arms being adapted to embrace and be connected to the adjacent flanged plate near its end face. 30

6. In a cattle guard comprising the usual A-frames and the usual ridged wooden strips attached to the tops of the ties, that improvement which consists in the provision of baffles adapted to be set beneath the rails and between the ties; 35 said baffles each being extensible and contractible longitudinally by adding or subtracting one or more like members which are connected together end for end to make up the complete baffle; each member having a height and width respectively substantially equal to the thickness of a tie and the distance between two ties. 40

7. The invention according to claim 6 wherein the members are flanged plates having means for adjustably connecting them to each other to permit adjacent members to be angular, offset or alined with each other. 45

S. IRMA SMITH.
